UNITED STATES PATENT OFFICE.

ALEXANDER T. BROWN AND ARTHUR J. BRIGGS, OF SYRACUSE, NEW YORK; SAID BRIGGS
ASSIGNOR TO SAID BROWN.

TYPE-WRITING MACHINE.

No. 889,102.

Specification of Letters Patent.

Patented May 26, 1908.

Application filed July 14, 1905. Serial No. 269,650.

To all whom it may concern:

Be it known that we, ALEXANDER T. BROWN and ARTHUR J. BRIGGS, citizens of the United States, and residents of Syracuse, in the county of Onondaga and State of New York, have invented certain new and useful Improvements in Type-Writing Machines, of which the following is a specification.

Our invention relates to ink ribbon mechanism for use in printing devices and more especially in typewriting machines.

One object of our invention is to provide means for controlling an ink ribbon having longitudinal stripes or fields of different characteristics, such, for example, as a ribbon inked with inks of different colors.

Another object of the invention is to provide an improved means for feeding an ink ribbon both transversely and longitudinally.

Another object is to provide an improved reversing device for an ink ribbon.

Other objects will appear hereinafter.

The invention consists in certain features of construction and combinations and arrangements of parts which will be fully set forth herein and particularly pointed out in the claims.

The invention is illustrated in the accompanying drawings in which,

Fig. 1 is a longitudinal vertical sectional view of a typewriting machine having our invention embodied therein. Fig. 2 is a horizontal sectional view through a spring drum and certain gearing forming part of the driving mechanism of the ink ribbon. Fig. 3 is a rear elevation of the machine. Fig. 4 is an isometric view of a part of the ribbon mechanism detached from the typewriting machine. Fig. 5 is an isometric view of part of the ribbon mechanism; and Fig. 6 is a left-hand side elevation of a part of said mechanism.

The present invention is applicable to a variety of printing devices, but it has been more especially designed for use in typewriting machines, and we have accordingly shown it applied to a Smith Premier typewriter. The main frame of this machine comprises side plates 1 connected together by a back plate 2. Posts 3 rising from said side plates support a top plate 4 on which are rails 5 which support a carriage 6 by means of ball or roller bearings. A platen 7 is mounted on said carriage. Said carriage is drawn across the machine by a spring drum 8 to which it is connected by a strap 9.

A feed rack 10 mounted on the carriage normally engages a pinion 11 which is geared to a shaft 12 which, at its rear end, carries an escapement wheel 13 which co-operates with feed dogs 14 mounted on the upper end of a vertical rock shaft 15 journaled in bearings on the top plate 4 and back plate 2. Said rock shaft 15 has near its lower end an arm 16 which is operated by arms 17 projecting from a universal bar or gate 18 which is operated by arms 19 projecting from key operative rock shafts 20. Said rock shafts are journaled at their rear ends in the back plate 2 and at their forward ends in angled frame plates 21 which constitutes the keyboard of the machine. The rock shafts at their forward ends carry arms 22 which are pivoted to key stems 23 which pass loosely through openings in the keyboard plates 21 and at their upper ends carry character keys 24. Each of the rock shafts is provided with a returning spring 25. Arms 26 projecting from the rock shafts 20 are connected by links 27 with type bars 28. The parts above referred to are, or may be, of the well known construction ordinarily used in the Smith Premier machine.

A right-hand ribbon spool 29 and a left-hand ribbon spool 30 have hollow axles which are loosely mounted on rods 31 (Figs. 3 and 6) which extend between the posts 3. Said spools are automatically reciprocated axially along said rods 31 in order to impart a transverse feed to the ribbon and they are also rotated on said rods in order to impart a longitudinal feed to the ribbon. Each of said ribbon spools has associated therewith a frame 32 preferably made of sheet metal and comprising curved arms 33 which embrace the two ends of the ribbon spool and the free ends of which are formed with openings in which the hollow axle of the spool is journaled. The arms 33 are connected together by a yoke bar or plate 34 which, when the spools are in position, stands vertically and extends upward into a fore and aft slot formed in the top plate 4, as best appears in Fig. 3. Within said slot, the yoke plate 34 has bent off therefrom ears 35 of a length a little less than the width of the slot, as shown in Fig. 3. The construction is such that the ribbon spool and its frame 32 are free to slide from front to back of the machine, but the frame 32 is prevented from turning by the walls of the slot in the top

plate, the yoke plate 34 coöperating with one of said walls, and the ears 35 with the other. The upper edge of the plate 34 serves as a ribbon guide above the top plate, the ribbon being led across the machine beneath the platen from one of these plates to the other, thence downward through the slots in the top plate to the ribbon spools.

As best shown in Figs. 1 and 3, the rear arm 33 of each frame 32 has projecting therefrom toward the middle of the machine, an arm 36 from which is bent off toward the rear of the machine an arm 37 having formed therein a vertical slot 38 into which a pin 39 projects from an arm 40 fixed to and rising from a rock shaft 41. The rock shaft 41 extends transversely across the machine, being journaled on coned screws 42 threaded through the two rear posts 3. The construction is such that if the rock shaft 41 be rocked back and forth the ribbon spools will be reciprocated, sliding axially on the rods 31. The rock shaft 41 is rocked for this purpose by an arm 43 projecting therefrom toward the rear of the machine and having a pitman 44 connected with its rear end, the upper end of said pitman being mounted on a wrist pin 45 projecting from the rear face of a wheel 46 which is geared to the spring drum 8. The longitudinal feed of the ribbon is effected by a second pitman 47 connected with a wrist pin 48 projecting from the rear face of a wheel 49 which is also geared to the spring drum.

The train of gearing for operating the pitmen 44 and 47 will be best understood by reference to Figs. 2 and 3. The spring drum and said train of gearing are both mounted on a rod 50 extending through one of the rear posts 3 and secured in position by a set screw 51 threaded through said post and engaging a flattened face of said rod. The spring is not shown in Fig. 2, but its inner end is connected to the hub 52 of a toothed wheel 53 which is controlled by a suitable device (not shown) for turning the same to regulate the tension of the spring and for retaining it in adjusted position. The spring drum has a hub 54 which is journaled on the rod 50 back of the hub 52. A ratchet wheel 55 and a gear wheel 56, either integral or rigidly connected together, are journaled on the hub 54 of the spring drum 8. Back of said hub and said gear wheel 56 a horizontally extending arm 57 is mounted on the rod 50 to which it is rigidly connected by a pin 58 extending through the end of said arm and into said rod. In the free end of the arm 57 is journaled a short shaft 59 on the rear end of which is rigidly mounted a gear wheel 60 that meshes with the gear wheel 56.

The wheel 46 which actuates the pitman 44, is rigidly mounted on the rear end of the shaft 59 and is secured on said shaft by a headed screw 62 threaded into the end of the

shaft. The pinion 49 which controls the pitman 47 meshes with the gear wheel 46 and is mounted or formed on the end of a short shaft 64 which is journaled in a longitudinal opening or hole formed in the end of the rod 50. In order to prevent the shaft 64 from slipping out of said hole a plate 65 is mounted on the rear face of the gear 46, and said plate is of such diameter as to lap over the teeth of the pinion 49. The gear 46 has twice as many teeth as the pinion 49 so that said pinion makes two turns to one turn of the gear, and consequently the pitman 47 makes two strokes to one stroke of the pitman 44. The ratchet wheel 55 is engaged by a spring-pressed operating pawl 66 pivoted at 67 to the rear face of the spring drum 8 and also by a retaining pawl 68 pivoted on a shouldered and headed screw 69 threaded into the rear end of the shaft 59. The pawl 66 operates to turn the ratchet wheel 55 when the carriage is moving toward the left and the pawl 68 prevents rotation of said ratchet wheel in the opposite direction when the carriage is being drawn toward the right. The wrist pins 45 and 48 consist of shouldered and headed screws threaded eccentrically into the rear faces of the gear 46 and the pinion 49. It will be perceived that the pitmen 44 and 47 are operated whenever the carriage is moving toward the left but not when the carriage is moving toward the right. The pitman 44 is connected with the arm 43 by a universal joint. To this end a ball 70 is formed or mounted on the rear end of said arm and the lower end of the link is formed with an opening having the general outline of a part of a sphere, the rear portion of said opening being of less diameter than the diameter of the ball 70. A plate 71 is secured to the front face of the lower part of the pitman 44 by a screw 72 and said plate is formed with an opening, also having the general outline of a portion of a sphere, the front part of said opening being of less diameter than the diameter of the ball 70. The plate 71 being applied to the ball from the front and the link 44 being applied thereto from the rear and said parts being secured together by the screw 72, the link has in effect an opening which is spherical and which cannot come off of the ball 70 but which is free to move thereon with a universal motion.

The wrist pin 45 may obviously be placed at any desired distance from the center of the wheel 46 so that any desired extent of transverse feed may be imparted to the ribbon. For example, said wrist pin may be so placed as to move the ribbon spools such a distance as to utilize the whole width of the ribbon at each reciprocation thereof. In the present instance, however, said wrist pin is set nearer to the center so as to impart a less extent of reciprocatory motion to the ribbon spools and the ribbon is made with a plurality of

longitudinal stripes or fields of different characteristics. For example, the forward part of the ribbon may be inked with black ink and the rear part with red ink and such a difference is indicated by the shading on the ink ribbon in the drawing. It will, of course, be understood that these fields may differ in other respects. For example, one of them may be for copying ink and the other for record ink. In the present instance the ribbon is shown with two stripes or fields and the parts are so proportioned that a sufficient extent of transverse feed is imparted to the ribbon to utilize substantially the whole width of one of said fields.

In order to provide for shifting the ribbon from one field to the other, the arm 43 is not rigidly mounted on the shaft 41, but is loosely mounted thereon and means are provided for changing the relationship of this arm to said shaft and to the arms 40. As the ribbon in the present case has two fields, provision is made for two such relationships. The left-hand arm 40 is provided with an elongated hub, as best shown in Fig. 5, which hub is rigidly secured to the shaft 41 by a pin 73 projecting through said hub and shaft. The arm 43 is one arm of an angled lever which is pivoted on the shaft 41 in a slot 74 (Fig. 5) formed in the hub of the arm 40. The other arm 75 of said lever extends downward and forward and has a cam plate 76 pivoted thereto by a shouldered and headed screw 77. Said cam plate is formed with an eccentric cam slot 78 into which a pin 79 extends from an arm 80 projecting toward the front of the machine from the arm 40. Said arm 80 is drawn downward, tending to move the ribbon spools toward the front of the machine, by a spring 81 which is connected at its upper end to an ear 82 projecting from the arm 80 and at its lower end to a pin 83 projecting from the arm 75. The cam slot 78 is formed at its upper end with a notch 84 into which the pin 79 is drawn by the spring 81 when the cam plate is forced toward the front of the machine, thus retaining the parts in that position. The notch 84 is of such form, however, that by applying force to the cam plate 76, said cam plate may be moved toward the back of the machine and the spring 81 will then draw the pin 79 to the lower end of the slot 78. In order to move the cam plate 76 to one or the other of its two positions, a rod 85 is pivoted thereto at 86 and extends toward the front of the machine, having a sliding bearing in a bracket 87 depending from one of the frame plates 21. The rod 85 is provided with a handle 88 by which said rod may be pushed toward the back of the machine or pulled toward the front of the machine. When said rod and the cam plate 76 are in their rear position, shown in Figs. 1 and 5, the pin 79 is in the lower end of the cam slot 78, and the arms 40

occupy their forward position with reference to the arm 43 and the ribbon has its rear field beneath the printing point. As the arm 43 is rocked by its pitman 44 with the parts in this position, the arm 40 will oscillate between its extreme rear position, shown in full lines in Fig. 1, to its extreme forward position, shown in dotted lines in said figure and the transverse feed of the ribbon will be confined to the red field. If the handle 88 be pulled toward the front of the machine until the pin 79 is seated in the notch 84, the arms 40 will be tilted back with relation to the arm 43 as shown in Fig. 6, and the ribbon spools will be moved to bring the black field of the ribbon into use. When the arm 43 is rocked by its pitman 44 with the parts in this position, the arms 40 will oscillate between their extreme rear positions, shown by full lines in Fig. 6, and their extreme forward positions, shown by dotted lines in said figure, and the transverse feed of the ribbon will be restricted to the black field. In case a ribbon having but one kind of ink is used, the operator will occasionally shift it from one field to the other so as to get the use of the entire surface of the ribbon.

By an inspection of Figs. 1 and 6 it will be observed that when the parts are in the position shown in the latter of said figures, in which the black stripe of the ribbon is in use, a line drawn from the center of the shaft 41, perpendicular to the shaft 31, will nearly bisect the angle between the two extreme positions of the arm 40 as said arm is rocked to impart a transverse feed to the ribbon. In this position of the parts, therefore, said ribbon receives a maximum extent of transverse feed. When the parts are in the position shown in Fig. 1, with the red stripe of the ribbon in use, the arm 40 forms an obtuse angle with the axis of the ribbon spool. As said arm 40 is rocked through the same angle in both instances, it is evident that in the latter case a less extent of transverse feed will be imparted to the ribbon than in the former case. It will be perceived therefore, that means are provided for imparting a reciprocatory transverse feed to the ribbon within either one of a plurality of widthwise fields and that the extent of this reciprocatory feed is less when one field is in use than when the other is in use. This is an advantage in a device of this character because in most instances where polychrome ribbons are used one sort of ink is used less than the other. In the instance here given as an illustration, where one stripe of the ribbon is red and the other black, the black ink would ordinarily be used a good deal more than the red ink so that it is an advantage to have the black stripe wider than the red stripe.

So far as we are aware, it is broadly new in ribbon mechanism to provide means for im-

parting to any one of a plurality of inked surfaces of any sort whatever, a transverse reciprocatory feed before the printing point, one of said surfaces having a greater extent 5 of transverse reciprocatory feed imparted thereto than the other; and this whether said inked surfaces form parts of the same ribbon as in the present instance, or whether said inked surfaces are on separate ribbons, or 10 whatever may be the character of said ink surfaces. In the present instance this difference in the extent of transverse feed is effected by changing the relation of the parts of the transverse feeding means, but as far as we 15 are aware it is new to effect this difference by any means whatever.

In order to impart a longitudinal feed to the ribbon the pitman 47 is operatively connected with two pawls 89, the upper ends of 20 which have bent off portions 90 adapted to engage ratchet teeth 91 extending, crown-tooth fashion, from the front face of the front flange of each of the ribbon spools. The pawls 89 are pivoted on shouldered and 25 headed screws 92 threaded into the free ends of arms 93 which are fixed on and extend toward the back of the machine from a rock shaft 94. Said rock shaft 94 extends across the machine beneath the system of rock 30 shafts 20 and is journaled at its ends on coned screws threaded through the side plates 1; or said rock shaft may be journaled in said side plates in any suitable manner. Each of the pawls 89 is formed near its lower 35 end with a rearwardly extending part 95, an opening in which is plugged with a disk of lead 96, thus weighting said lever and causing it to tend to fall by gravity into engagement with its ratchet wheel. As will appear 40 hereinafter, means are provided for holding one or the other of the pawls out of engagement with its ratchet wheel. It will be obvious that if preferred the pawls may be pressed toward the ratchet wheel by springs 45 instead of by gravity as in the present instance. An arm 97 fixed to and rising from one end of the rock shaft 94, has pivoted thereto on a shouldered and headed screw 98, a link 99 which extends upward and toward 50 the back of the machine, its rear end being pivoted at 100 to a downwardly extending arm 101 of a lever having a rearwardly extending arm 102 which is connected with the pitman 47 in the same manner as the arm 43 55 to the pitman 44. The lever 101, 102 is pivoted on the rock shaft 41. In order to afford a wide bearing for said lever and to prevent motion thereof endwise of the shaft 41, said lever is mounted on said shaft just to the 60 left of the hub of the left-hand arm 40 and the arm 101 has bent off therefrom an arm 103 parallel with the shaft 41 and said arm 103 is again bent, forming an arm 104 which is pivoted on the rock shaft 41 to the right of 65 the hub of the arm 40. The construction is

such that as the pinion 49 is rotated and the pitman 47 reciprocated, the lever 101, 102 is rocked, thus rocking the shaft 94 by means of the link 99, and moving the pawls 89 up and down in unison. Both pawls operate on the inner sides of their respective ratchets and their up-strokes are their operating strokes in both instances. As the up-stroke of the pawls 89 is effected on the down-stroke of the pitman 47, that one of the ribbon spools which has its pawl in engagement with its ratchet will be turned a short distance to feed the ribbon longitudinally upon each down-stroke of the pitman 47. As has been said above the pitman 47 makes two strokes to one stroke of the pitman 44. The parts are so arranged that the pitman 47 is about in the middle of its operating stroke at the moment when the pitman 44 is on the dead center, so that the longitudinal feed of the ribbon begins just before the ribbon has reached one end of one of its reciprocations and reaches its maximum velocity just at the end of said reciprocation and is completed soon after the beginning of the transverse motion of the ribbon in the other direction. Obviously, as the pinion 49 makes one turn to each half turn of the gear 46, the pitman 47 will make an operating stroke at about the time when the pitman 44 is at the limit of its down-stroke and another at about the time when the pitman 44 is at the end of its up-stroke, so that a longitudinal feed will be imparted to the ribbon at each end of each transverse reciprocation thereof. In Fig. 3 the pitman 47 is shown about at the end of its operating stroke and the pitman 44 a little past the dead center on the beginning of its up-stroke. In this position of the parts one step of longitudinal feed has just been completed. The pawls 89 are of considerable length and follow the spools in their axial motion so that one of said pawls is always in operative position whether the spools are set to use the red field or the black field.

In order to reverse the direction of longitudinal feed of the ribbon we have provided means for holding one or the other of the pawls 89 toward the front of the machine, and out of engagement with the ratchet. Said means comprises two arms or levers 105 having hubs 106 journaled on the rock shaft 94. Said hubs are held against endwise motion in one direction by the hubs of the arms 93 and in the other direction by collars 107 secured to the rock shaft 94 by set screws. Each of the arms or levers 105 at its upper end is bent to form a long loop 108 through which one of the pawls 89 passes. The loops 108 are closed at the rear so that if one of the arms 105 be drawn toward the front of the machine it will draw the pawl 89 away from its ratchet and said pawl will play idly up and down in said loop when the machine is in op-

eration. In order to control the levers 105 so as to cause one of them to occupy its rear position, permitting its pawl to operate on its ratchet when the other occupies its forward position holding its pawl inoperative, each of said levers has a forwardly extending arm 109 to which is pivoted at 110 an upwardly extending link 111. A rock shaft 112 is pivoted at its ends to the side plates 1 and extends across the machine above the system of key operated rock shafts 20. Two upwardly extending arms 113 are rigidly mounted on said rock shaft 112, one near each end thereof. To this end each of said arms is provided with a hub 114 which is secured to the rock shaft 112 by a setscrew 115. One of the arms 113 has an arm 116 extending therefrom toward the rear of the machine and one of the links 111 is pivoted at its upper end to this arm. The other of the arms 113 has an arm 117 extending therefrom toward the front of the machine and the other of the links 111 is pivoted at its upper end to this arm 117. The construction is such that if the shaft 112 be rocked toward the rear of the machine, the arm 116 will depress its link 111 and rock the arm 105 toward the front of the machine. At the same time the arm 117 will elevate its link 111 and move its arm 105 toward the rear of the machine. If the rock shaft be rocked toward the front of the machine, the arm 116 will rise and the arm 117 will be depressed, thus reversing the relative positions of the two arms 105 and 35 moving to inoperative position that pawl which was before in operative position and permitting the other pawl to fall to operative position, thus reversing the direction of feed of the ribbon. A handle 118 is mounted on one of the arms 113 so that the shaft 112 may be rocked by hand. In order to yieldingly retain the rock shaft 112 in either of its two positions, the arm 117 is extended and the forward free end thereof is beveled in 45 both directions, as shown at 119; the pointed end 119 thus formed is engaged by a roller 120 journaled in the free end of a spring arm 121 which depends from one of the frame plates 21. The roller 120 will yield to permit the pointed end 119 of the arm 117 to pass it in either direction if sufficient force be applied to said arm, but said roller will retain the arm in either of its positions. In 55 order to limit the forward movement of the pawls 89, each of the arms 113 has projecting therefrom a bracket 122 which stands in the path of a part of the pawl when said pawl is moved away from its ratchet wheel.

We have provided means for automatically reversing the feed of the ink ribbon whenever said ribbon is exhausted from one of the spools. Each of the ribbon spools 29 and 30 has a drum portion 123 on which the ribbon is wound and which is formed with an opening 124 (Fig. 4) into which an arm or arms

125 of a plate 126 are adapted to drop when the ribbon is exhausted from the spool. The plate 126 is mounted on a rock shaft 127 which lies parallel to the axis of the ribbon spool and is journaled in the arms 33. The plate 126 is secured to the rock shaft 127 by rivets 70 128. Each of the shafts 127 projects through the forward one of the arms 33 and is bent off to form an arm 129. Each of the arms 113 on the rock shaft 112 has at its upper end 75 an arm 130 extending therefrom toward the back of the machine and said arm 130 has formed thereon two lugs 131 and 132, the latter being nearer the front of the machine than the former. The operation of this device in the case of the right-hand ribbon spool is as follows:—When the ribbon is wound on this spool the arms 125 of the plate 126 ride out of the openings 124 on to the drum 123 and with the first turn of the spool 80 said arms rest on the ribbon itself, which thus closes the openings 124. When the ribbon is being fed off of this particular spool, the arms 125 will rest on the ribbon until the last turn of the spool, when, this 90 portion of the drum 123 being now exposed, the arms 125 will drop into the openings 124. The parts are so proportioned that when said arms drop into said openings the free end of the arm 129 moves toward the middle of the 95 machine to such an extent that it stands behind one of the lugs 131 or 132 on the arm 130. When the spool is next moved toward the front of the machine in the course of its transverse feed, the arm 129 engaging the lug 100 pushes the arm 113 toward the front of the machine, thus rocking the rock shaft 112 and moving the left-hand pawl 89 out of engagement with its ratchet and permitting the right-hand pawl 89 to drop into engagement 105 with its ratchet, thus reversing the longitudinal feed. If the ribbon spools are set to use the forward stripe or field, the arm 129 will engage the rear lug 131; but if the spools are set to use the rear stripe or field of the 110 ribbon said arm will engage the forward lug 132, so that the reverse will take place equally well whichever field of the ribbon happens to be in use at the time. It will be perceived that the reverse is effected by the 115 transverse feed of the ribbon and that it may be effected when either field of the ribbon is in use. If the ribbon were made with only one field so that the transverse feed extended the whole width of the ribbon it is obvious 120 that but one of the lugs 131 or 132 would be necessary. Furthermore, if the ribbon had more than two fields a corresponding number of such lugs would be provided. The construction and operation of the reversing 125 mechanism for the left-hand ribbon spool are substantially identical with that for the right-hand ribbon spool, except for the fact that the left-hand spool is arranged to move its arm 113 toward the rear of the machine. 130

- Consequently the arm 129 connected with the left-hand spool drops in front of the lug 131 or 132 instead of behind said lug as in the case of the right-hand spool. The arms 113 are conveniently made of sheet metal and the lugs 131, 132 may be stamped out of the metal. The lugs on the right-hand arm 113 are made with abrupt rear faces and inclined forward faces, while those lugs on the left-hand arm 113 are made with abrupt forward and inclined rear faces. Moreover the lugs on the left-hand arm 113 are a little nearer the rear of the machine than those on the right hand arm, as will be understood.
- 15 The forward faces of the lugs on the right-hand arm and the rear faces of the lugs on the left-hand arm are made beveled so that in case the arms 125 drop into the openings 124 when the arm 129 is forward of the lug,
- 20 in the case of the right-hand spool, or back of the lug in the case of the left-hand spool, said arm will ride over the lug as the spool is reciprocated by the transverse feed mechanism.
- 25 Various changes may be made in the details of construction and arrangements of parts without departing from our invention.
- What we claim as new and desire to secure by Letters Patent, is:—
- 30 1. In a typewriting machine, the combination of a ribbon having a plurality of different widthwise fields; means for giving an automatic transverse and an automatic longitudinal feed to the ribbon and for confining the feed to any desired transverse field; and means for automatically reversing the longitudinal feed of the ribbon, the operation of said reversing means being effected by the transverse feed of the ribbon.
- 40 2. In a typewriting machine, the combination of ribbon spools, automatic means for imparting to said spools an axial movement to effect a transverse feed of the ribbon within any one of a plurality of widthwise
- 45 fields of the ribbon; means for determining which widthwise field shall be presented at the printing center; and means controlled by the axial feed of the ribbon spools for automatically effecting a reversal in the direction of longitudinal feed of the ribbon.
- 55 3. In a typewriting machine, the combination of ribbon spools, automatic means for imparting to said spools an axial movement during the operation of the machine to effect a transverse feed of the ribbon within any one of a plurality of widthwise fields of the ribbon; hand actuated means for determining which widthwise field shall be presented at the printing center; and means controlled by
- 60 the axial feed of the ribbon spools when any field is at the printing center for automatically effecting a reversal in the direction of longitudinal feed of the ribbon.
- 65 4. In a typewriting machine, the combination of ribbon spools, automatic means for

imparting to said spools an axial movement to effect a transverse feed of the ribbon within any one of a plurality of widthwise fields of the ribbon; hand actuated means for changing the relation of the parts of said means for effecting the axial feed movements of the spools and for effecting axial shifting movements of the spools to present any desired widthwise field of the ribbon to the printing center; and means controlled by the axial feed of the ribbon spools for automatically effecting a reversal in the direction of longitudinal feed of the ribbon.

5. In a typewriting machine, the combination of ribbon spools; means for automatically turning said ribbon spools for effecting a longitudinal feed of the ribbon; means for automatically effecting an axial feed of the ribbon spools to produce a transverse feed of the ribbon; hand actuated means for determining which of a plurality of widthwise fields of the ribbon shall be presented at the printing center whereby the feed of the ribbon will be confined so as to present said field only to the action of the types; and automatically actuating means controlled by the axial feed of the ribbon spools for reversing the direction of longitudinal feed of the ribbon.

6. In a typewriting machine, the combination of a ribbon having a plurality of widthwise fields of different characteristics; means for effecting a longitudinal and transverse feed of the ribbon and for confining any desired field of the ribbon to the action of the types to the exclusion of the other field or fields; means controlled by the transverse feed of the ribbon for automatically reversing the direction of longitudinal feed thereof; and means automatically controlled by the ribbon for determining when the transverse feed of the ribbon shall be rendered effective to effect a reversal in the direction of the longitudinal feed thereof.

7. In a typewriting machine, the combination of ribbon spools; means for automatically turning said ribbon spools for effecting a longitudinal feed of the ribbon; means for automatically effecting an axial feed of the ribbon spools to produce a transverse feed of the ribbon; hand actuated means for determining which of a plurality of widthwise fields of the ribbon shall be presented at the printing center whereby the feed of the ribbon will be confined so as to present only said field to the action of the types; automatically actuated means controlled by the axial feed of the ribbon spools for reversing the direction of longitudinal feed of the ribbon; and means controlled by the ribbon when an end thereof is approached to automatically render the axial feed movements of the ribbon spools effective to reverse the direction of longitudinal feed of the ribbon.

8. In a typewriting machine, the combina-

- tion of ribbon spools, automatic means for imparting to said spools an axial movement to effect a transverse feed of the ribbon within any one of a plurality of widthwise fields of the ribbon; hand actuated means for changing the relation of the parts of said means for effecting the axial feed movements of the spools and for effecting axial shifting movements of the spools to present any desired widthwise field of the ribbon to the printing center; means controlled by the axial feed of the ribbon spools for automatically effecting a reversal in the direction of longitudinal feed of the ribbon; and means controlled by the ribbon when an end thereof is approached to automatically render the axial feed movements of the ribbon spools effective to reverse the direction of longitudinal feed of the ribbon.
9. In a typewriting machine, the combination of ribbon spools; automatically driven shafts therefor and with which the ribbon spools turn and on which they are adapted to receive axial feed movement and axial shifting movements to bring different widthwise fields of the ribbon into coöperation with the printing instrumentalities; means for automatically effecting an axial feed of the ribbon spools; and automatic means operated by the axial feed of the ribbon spools for changing the direction of rotation of the ribbon spools when an end of the ribbon is approached.
10. In a typewriting machine, the combination of ribbon spools; automatically driven shafts therefor and with which the ribbon spools turn and on which they are adapted to receive axial feed movement and axial shifting movements to bring different widthwise fields of the ribbon into coöperation with the printing instrumentalities; means for automatically effecting an axial feed of the ribbon spools; hand actuated means for effecting an axial shift of the ribbon spools on their shafts to bring any desired widthwise field of the ribbon into coöperation with the printing instrumentalities, and automatic means operated by the axial feed of the ribbon spools for changing the direction of rotation of the ribbon spools when an end of the ribbon is approached.
11. In a typewriting machine, the combination of a carriage; a wheel that is operatively connected to rotate during the feed movement of said carriage; ribbon spools; means for automatically rotating said ribbon spools; means controlled by said wheel for automatically effecting axial feed movements of said spools; hand actuated means for shifting the ribbon spools axially to bring any desired widthwise field of the ribbon to position where it may coöperate with the printing instrumentalities to the exclusion of the other widthwise field or fields and without affecting the longitudinal and transverse

feed of the ribbon; and means controlled by the axial feed of the ribbon spools for automatically reversing the direction of longitudinal feed of the ribbon.

12. In a ribbon mechanism, the combination with ribbon spools and ribbon guides, of driving means including rotary devices and two pitmen operated thereby; means operated by one of said pitmen for imparting a transverse feed to the ribbon; and means operated by the other of said pitmen for imparting a longitudinal feed to said ribbon.

13. In a ribbon mechanism, the combination with spools and guiding means for an ink ribbon, of driving means including rotary devices and two pitmen operated thereby; means operated by one of said pitmen for imparting a reciprocatory transverse feed to the ribbon; and means operated by the other of said pitmen for imparting a longitudinal feed to the ribbon substantially at the end of each transverse reciprocation.

14. In a ribbon mechanism, the combination with spools and guiding means for an ink ribbon, of driving means including rotary devices and two pitmen operated thereby; means for imparting reciprocatory motion to said pitmen, said means being adapted to impart twice as many reciprocations to one of said pitmen as the other; means operated by the latter of said pitmen for imparting a transverse reciprocatory feed to said ribbon; and means operated by the former of said pitmen for imparting a longitudinal feed to the ribbon substantially at each end of its transverse reciprocatory motion.

15. In a ribbon mechanism, the combination with spools and guiding means for an ink ribbon, of driving means including two cranks, one of which makes two turns to one turn of the other; pitmen operated by said cranks; means operated by the slower pitman for imparting a reciprocatory transverse feed to the ribbon; and means operated by the faster pitman for imparting a longitudinal feed to the ribbon.

16. In a ribbon mechanism, the combination with spools and guiding means for an ink ribbon, of driving means including two wheels geared together, one of said wheels making twice as many rotations as the other; a crank pin on each of said wheels; a pitman connected with each crank pin; means operated by the slower pitman for imparting a reciprocatory transverse feed to the ribbon; and means operated by the faster pitman for imparting a longitudinal feed to the ribbon substantially at the end of each reciprocation thereof.

17. In a ribbon mechanism, the combination with spools and guiding means for an ink ribbon, of driving means including two rotary members geared together so that one of said members makes twice as many turns as the other; a pitman eccentrically mounted

- on each of said rotary members in such fashion that the pitman of the faster rotary member is making its operative stroke at about the time that the pitman of the slower member is on the dead center; means operated by the slower pitman for imparting a reciprocatory transverse feed to the ribbon; and means operated by the faster pitman for imparting a longitudinal feed to the ribbon.
- 10 18. In a ribbon mechanism, the combination with spools and guiding means for an ink ribbon, a rotary driving means; two pitmen operated by said rotary driving means; means operated by one of said pitmen for moving said ribbon spools axially to impart a reciprocatory transverse feed to said ribbon; and pawls operated by the other of said pitmen for rotating said spools.
- 15 19. In a ribbon mechanism, the combination with guiding means and two spools for an ink ribbon, of means for imparting a reciprocatory transverse feed to said ink ribbon; a pawl for driving one of said spools; and means for operating said pawl, said means operating to give to said pawl an operative stroke substantially at each end of each transverse reciprocation of said ink ribbon and to impart to said pawl its return stroke during the transverse movement of 20 the ribbon.
- 20 20. In a ribbon mechanism, the combination of two ribbon spools; two pawls for operating said ribbon spools; a rock shaft having arms with which said pawls are connected; two guide arms loosely mounted on said rock shaft; and means for simultaneously moving said arms in opposite directions to move one of said pawls to operative and the other to inoperative position.
- 25 21. In a ribbon mechanism, the combination of two ribbon spools; two pawls for operating said ribbon spools; two guides for said pawls; a rock shaft; and connections between said rock shaft and said guides for moving said guides in opposite directions to move one of said pawls to operative and the other to inoperative position.
- 30 22. In a ribbon mechanism, the combination of two ribbon spools; two pawls for operating said ribbon spools; two guides for said pawls; a rock shaft; connections between said rock shaft and said guides for moving said guides in opposite directions to move one of said pawls to operative and the other to inoperative position; and automatic ribbon controlled means for rocking said rock shaft.
- 35 23. In an ink ribbon mechanism, the combination with spools and guiding means for an ink ribbon, of a rock shaft; arms on said rock shaft adapted to impart a transverse feed to said ink ribbon; a lever mounted on said shaft; driving means for oscillating said lever; a connecting member between said lever and said shaft for transmitting the motion of said lever to said shaft, said connecting member being adjustable to vary the angular relation between said lever and said shaft so as to bring different fields of the ink ribbon into use; a link pivoted to said connecting member and extending toward the front of the machine; and a handle connected with said link.
- 40 24. In an ink ribbon mechanism, the combination with spools and guiding means for an ink ribbon, of a rock shaft having arms adapted to impart a transverse feed to said ink ribbon; a lever mounted on said rock shaft; driving means for oscillating said lever; a connecting member for transmitting the motion of said lever to said rock shaft, said connecting member being pivoted to one of the parts which it connects and having a pin and cam-slot connection with the other of said members, whereby the angular relation between said lever and said rock shaft may be varied by adjusting said connecting member; a link pivoted to said connecting member; and a handle for operating said link.
- 45 25. In an ink ribbon mechanism, the combination with spools and guiding means for an ink ribbon, of means for moving said spools axially to impart a transverse feed to said ribbon; a pawl for turning one of said spools to impart a longitudinal feed to the ribbon; and means for imparting an operating stroke to said pawl in the same direction substantially at each end of each axial reciprocation of the ribbon spools.
- 50 26. In an ink ribbon mechanism, the combination with guiding means and two spools for an ink ribbon, of two pawls, one for each spool; and a reversing device for said ribbon mechanism including two pivoted guide arms for said spools, an oscillatory member, and means connected with said oscillatory member for rocking said guide arms in opposite directions to cause one of said pawls to move to operative and the other to inoperative position.
- 55 27. In an ink ribbon mechanism, the combination with guiding means and two spools for an ink ribbon, of means for imparting a longitudinal feed to said ink ribbon; means for imparting to said ink ribbon a reciprocatory transverse feed within any one of a plurality of widthwise fields; and a reversing device comprising a member having a plurality of tappets, one for each of said widthwise fields, and a contact member adapted to move to operative position when the ribbon is nearly exhausted from one of the spools and adapted when in operative position to engage one of said tappets and to move the same during the transverse motion of said ribbon to reverse the direction of the longitudinal feed of the ribbon.
- 60 28. In an ink ribbon mechanism, the combination with guiding means and two spools

for an ink ribbon, of means for imparting to said ribbon a reciprocatory transverse feed within any one of a plurality of widthwise fields; means for imparting a longitudinal feed to said ribbon; and means for reversing the direction of said longitudinal feed, said reversing means comprising a rock shaft, two arms mounted on said rock shaft, one adjacent to each of said spools, a plurality of 10 tappets on each of said arms, one tappet for each of said widthwise fields, and a contact device adapted to move to operative position when the ribbon is nearly exhausted from one of the spools and when so moved to engage 15 one of said tappets and thereby to rock said rock shaft to reverse the feed when the ribbon is moving transversely.

29. In an ink ribbon mechanism, the combination of two inked surfaces of different widths, and means for imparting to either of said inked surfaces a reciprocatory transverse feed before the printing point of an extent appropriate to the width of that surface.

30. In an ink ribbon mechanism, the combination with spools and guiding means for an ink ribbon, of means for imparting a transverse feed to said ribbon within any one of a plurality of widthwise fields, said means being adapted to impart a greater extent of transverse feed to said ribbon within one of 25 said fields than within another.

31. In an ink ribbon mechanism, the combination of two inked ribbon surfaces of different characteristics; shifting means for bringing one or another of said ribbon surfaces to a common printing point, and means for imparting to said ribbon surfaces a transverse feed before the printing point, one of said surfaces having a greater extent of transverse feed before the printing point than the other.

32. In an ink ribbon mechanism, the combination of two inked ribbon surfaces; shifting means for bringing one or the other of said inked surfaces to a common printing point; means for imparting a reciprocatory transverse feed to one of said inked surfaces before the printing point; said shifting means being adapted to change the relation of the 45 parts of said transverse feeding means so that one of said inked surfaces has a greater extent of transverse feed before the printing point than the other.

33. In a typewriting machine, the combi-

nation with printing instrumentalities and a carriage, of means for driving said carriage; rotary devices geared to said carriage driving means; two reciprocatory members actuated by said rotary devices; an ink ribbon; means operated by one of said reciprocatory members for imparting a longitudinal feed to said ink ribbon; and means operated by the other of said reciprocatory members for imparting a transverse feed to the ink ribbon.

34. In a typewriting machine, the combination with printing instrumentalities and a carriage, of driving means for said carriage; rotary devices actuated by said driving means; two reciprocatory members actuated by said rotary devices, one of said reciprocatory members being arranged to make twice as many strokes as the other; an ink ribbon; means operated by the slower of said reciprocatory members for imparting a transverse feed to said ink ribbon; and a pawl operated by the faster of said reciprocatory members for imparting a longitudinal feed to said ribbon.

35. In a typewriting machine, the combination with type operating means and a carriage, of carriage driving means; a rock shaft 41, rocked by said carriage driving means; an ink ribbon; means operated by said rock shaft 41 for imparting a transverse feed to said ink ribbon; a rock shaft 94 operated by 85 said carriage driving means; and pawls connected with said rock shaft 94 and arranged to impart a longitudinal feed to the ribbon.

36. In a typewriting machine, the combination with type operating means and an ink ribbon, of pawls 89 for imparting a longitudinal feed to said ink ribbon; a rock shaft 112; guides 105 for controlling said pawls; and links 111 connecting said rock shaft 112 with said guide arms in such fashion that 95 when said rock shaft is rocked in one direction one of said guide arms affords a motion of its pawl to inoperative position and the other of said guide arms affords a motion of its pawl to operative position.

Signed at Syracuse, in the county of Onondaga and State of New York.
